METHOD OF OPERATING ELECTRICAL
SPACE DISCHARGE DEVICESLaurence K. Marshall, Cambridge, Mass., assignor
to Raytheon Manufacturing Company, Newton,
Mass., a corporation of Delaware

Application September 10, 1942, Serial No. 457,803

2 Claims. (Cl. 250—27.)

1

This invention relates to a method of operating electrical space discharge devices of the type having directly heated thermionic cathodes, such as filamentary cathodes.

For certain purposes, such as for example in pulsing applications, tubes are required to intermittently conduct peak currents. To satisfy such peak current requirements, it has heretofore been the practice to use tubes of relatively large current-conducting capacity, i. e. tubes whose cathodes at their usual operating temperature supply sufficient emission for such peak current requirements. According to this practice, such cathodes are operated at their usual operating temperatures, both during peak periods and non-peak periods. However, this practice is inefficient because during non-peak periods the temperature required for peak emission exceeds the non-peak requirements. Furthermore, in relation to non-peak period requirements, the tubes employed in this practice are unnecessarily large and expensive.

In applications where peak periods are relatively short compared to non-peak periods, this inefficiency becomes more pronounced. For example, in one specific pulsing application, a tube is required to conduct about 1000 peak pulses per second, each of said pulses having a duration of approximately one microsecond. Peak emission is therefore required for 1000 microseconds each second or $1/1000$ of a second. During the remaining $999/1000$ of each second, this peak emission is excessive. It is therefore apparent that when the peak periods are relatively short, the inefficiency of such prior practice is great.

An object of the present invention is to provide a more efficient method of operating tubes, particularly in systems where said tubes are required to conduct peak currents whose duration is small compared with the duration of the non-peak currents.

Another object of the present invention is the provision of a method of operating tubes in such systems which enables the use of smaller tubes than heretofore required.

Ordinary attempts to use cathodes having higher peak emission currents introduce the danger of excessive evaporation of cathode material. A still further object, therefore, is to operate a given cathode at high peak emission currents with substantial reduction in the evaporation of cathode material.

Other and further objects of the present invention will become apparent and the foregoing will be best understood from the following de-

2

scription of an exemplification thereof, reference being had to the drawing in which the figure is a schematic diagram of a system utilizing my invention.

6 Electronic tubes are designed to have their cathodes operated at a usual or rated temperature. At the rated temperature a given rate of emission is produced. If the cathode is operated above its rated temperature, an increase in emission will occur. This is expressed in the generally accepted Richardson equation as follows:

$$I_s = AT^2 e^{-w/kT}$$

in which I_s is the saturation current per unit

- 15 area of emitter, T is the absolute temperature, w is the electronic affinity of the emitter (work function), k is Boltzmann's universal gas constant, A is a constant for the emitting material, and e is the Napierian base. It will be apparent
- 20 from an examination of this equation that a slight rise in temperature will produce a large increase in the rate of emission. However, when cathodes are operated above their rated temperature, certain deleterious effects ensue, such as, for example, evaporation of the cathode material and settling of the evaporated material on the electrodes and other metal parts of the tube, thereby producing undesirable secondary emission. In addition to the foregoing, the operative life of
- 25 coated cathodes is inordinately shortened due to the rapid evaporation of the coating material at such higher temperatures. The rated temperature of a cathode is, therefore, usually a compromise representing the maximum emission obtainable under ordinary methods of operation
- 30 without the introduction of substantial deleterious effects, and with allowance for a reasonably long operative life, such as, for example, 1000 hours or several thousand hours.

- 35 40 Heretofore the greater emission obtainable at temperatures above the rated temperature has been considered practically unavailable because of the aforementioned deleterious effects. However, I have discovered how to obtain this greater emission while substantially avoiding these effects. My invention will be best understood in connection with the accompanying drawing in which the system there illustrated includes an oscillator 1 used in conjunction with a pulsing device 2. The pulsing device 2 may be of any well-known type such as is used for any suitable purpose, for example in transmitter devices, etc. The oscillator 1 includes an electrical space discharge device or tube 3 having a cathode 4 of the directly energized type, such as, for example, a fila-
- 45
- 50
- 55

mentary cathode. Tube 3 is provided with an anode 5 and may be provided with a suitable control means, such as a control grid 6.

Since this invention relates particularly to the method of operating the cathode of such tubes, the details of the pulsing device and the oscillator are here omitted, especially since such details will be readily apparent to those versed in the art. This description is therefore directed to the method of operating the cathode.

The cathode 4 may be supplied with a steady current, alternating or direct, to heat it to a temperature below that required for peak-current requirements. This may be its rated temperature or below its rated temperature. At this temperature the cathode only produces sufficient emission for non-peak current requirements. For this purpose any suitable source of current may be utilized, preferably a direct current, which may be derived from a battery 7. In order to heat the cathode 4 to produce the peak emission required, I prefer to utilize the discharge from a condenser 8. The capacity of condenser 8 is determined by the duration of the peak pulses to be conducted by tube 3, and the energy to be supplied to the cathode. In the embodiment illustrated, condenser 8 may have a capacity of the order of $\frac{1}{2}$ a microfarad and be charged to a voltage of the order of 1000 volts. A charging voltage of about 2000 volts could be conveniently utilized. The temperature of the cathode is substantially raised by the energy of the discharge, and this rise in temperature may be of the order of several hundred degrees centigrade, the heat expended being approximately .3 joule. These constants, of course, must be selected in accordance with the specific conditions encountered.

It is preferred that condenser 8 supply energy to produce the required peak emission only during the time that such peak emission is required. Since the time constant of a condenser discharge circuit is equal to $R \times C$, it will be seen that the resistance of the particular circuit into which the condenser discharges, as well as the capacity thereof, determine the rate of discharge. By choosing the proper constants for the condenser and the circuit into which it discharges, it will be readily apparent that the discharge of the condenser may be so timed as to produce the desired peak emission only during such periods as such peak emission is required.

In the illustrated pulsing system, each peak pulse may have the duration of the order of a microsecond, there being approximately 1000 such pulses per second, each pulse consisting of oscillations having a high frequency, such as, for example, from 300 to 1500 megacycles. The effective duration of each condenser discharge may therefore be of the order of a microsecond. The time intervening between shots of energy supplied to the cathode will be of the order of 1000 microseconds, and the duration of such shots of energy relative to the time between shots will be approximately of the order of 1 to 1000. It is of course apparent that these constants may be varied within considerably wide limits depending upon the particular conditions to be met. For example, the ratio between the duration of the shots of energy for heating the cathode and the time between such shots may be as low as 1 to 100, and practically may be as high as one to several thousands.

While it is desirable for maximum efficiency that the shots of energy supplied to the cathode shall not continue for a period longer than the

period during which peak emission is required, such shots may have a considerably shorter duration than the time required for peak emission. Since a definite amount of time is required for

5 the energy supplied to the cathodes to be dissipated and for the cathode temperature to fall to a temperature of non-peak emission, advantage may be taken of this thermal lag by supplying the energy required for peak emission during

10 a period of time considerably shorter than the time for which such peak emission is required. Due to the thermal lag the temperature of the cathode will not drop immediately and the emission of said cathode will be gradually reduced

15 over a period of time which by proper proportioning of the constants of this system will be sufficient to supply peak emission during the entire period in which such emission is required.

In order that the deleterious effects attendant 20 upon operation of the cathode above its rated temperature be avoided, or kept to a minimum, it is desirable that during periods where peak emission is no longer required, the temperature of said cathode should fall rapidly to its rated temperature, or even below that. For this purpose it is

25 desirable to utilize a tube having a cathode which will rapidly dissipate heat. Such a cathode preferably has the maximum surface for the minimum volume. One form of cathode satisfactory

30 for this purpose is the thin ribbon type of filament.

It is preferred that condenser 8 be discharged through a low impedance path so that the discharge will have a steep wave front. This steep 35 wave front takes advantage of the "skin effect," concentrating the energy derived from condenser 8 at the surface of the cathode at precisely the point where emission occurs. The temperature of the surface of the cathode is thereby practically instantaneously raised to the temperature required to produce the desired peak emission while less of the energy of the discharge is wasted in unnecessarily heating the interior core of the cathode.

40 45 Since condenser 8 is to be discharged at a rapid rate I prefer to use a vacuum tube relay 9 to control the discharge thereof. Since the ordinary vacuum tube relay may be incapable of handling the required amount of current necessary to produce peak emission from the cathode 4,

I prefer to have the condenser 8 discharge into the primary 10 of a step-down air core transformer 11. Thus, the vacuum tube relay 9 is only required to handle comparatively small currents at comparatively high voltage, the larger currents required for peak emission being generated in the secondary 12 of the step-down transformer 11. The secondary 12 may consist of only a few turns, and in order to reduce to a minimum any leakage inductance with its attendant impedances the primary 10 and the secondary 12 are as closely coupled as possible. For this purpose the secondary 12 may consist of one or more turns of a conducting ribbon closely wound around the primary 10. The secondary 12 of the step-down transformer 11 is preferably arranged in series with the cathode 4 and the battery 7. Because of the high capacity of the battery 7, it will offer little impedance to the pulses of current generated in the secondary 12. Condenser 8 may be charged by any suitable source of direct current 14, such as, for example, a battery, rectifier, or direct current generator, etc. A current limiting resistance 15 may be arranged in series with the

The operating power as contrasted with the cathode heating power is supplied to the oscillator 1 from a triggered power supply 16 of any well-known type. The device 16 is triggered off for the proper length of time at the proper time intervals by triggering impulses supplied through lines 17.

If, in heating cathode 4 to produce peak emission, a thermal lag is found to exist which would substantially delay the production of peak emission and thereby affect the operation of the system, this may be corrected by causing condenser 8 to discharge a short interval of time before peak current is required from tube 3. For this purpose a suitable pulse-delaying means 18 may be connected between the pulsing device 2 and the lines 17, and may be adjusted so that the vacuum tube relay causes condenser 8 to discharge a short time before tube 3 is required to conduct peak current. Such pulse-delaying devices are, of course, well known, and need not be described in detail herein. A quite common means for delaying the pulses is to employ the equivalent of a long transmission line made up of a plurality of condensers and reactors. The output of the oscillator 1 may be delivered to any suitable utilization device, which may be, for example, a radiating system 19.

By the method hereinabove described, it is possible to obtain several times the normal peak output of a tube in such systems. This high output is obtained without inordinately shortening of the life of the tube and without other substantial deleterious effects. I believe that this is due in part to the relatively short duration of the pulses of current supplied to the cathode and also to other factors, such as, for example, the steep wave front of such pulses. It is to be noted that in the instances cited, the time intervening between pulses of current supplied to the cathode is considerably greater than the duration of said pulses. Thus the temperature of the cathode may fall back to approximately its rated temperature or perhaps below its rated temperature during the time intervening between successive pulses. The average temperature of the cathode may be below or substantially equal to its rated temperature.

In the system hereinabove described, pulses of current for heating the cathode are used in conjunction with an additional source of heating current. With certain types of tubes and in certain systems it is feasible to use pulses of current without any additional source of current for heating the cathode. By proper timing of the discharge of the condenser, or other means utilized for supplying pulses of current to the cathode, the cathode may be heated so as to produce the desired peak emission only at such times as such peak emission is required.

As has been pointed out before, the rate of emission increases more rapidly than does the temperature. Therefore, it is possible by my method to obtain an average emission considerably greater than the average emission obtained by operating a cathode at its rated temperature. While I have described my method as applied in a system in which peak pulses occur intermittently, it is feasible to employ my method to obtain a higher output from a given tube in any system where the fact that the emission is pro-

duced in intermittent peaks will not prevent proper operation of such system and where such system is able to utilize the increased average emission.

While I have described my method in conjunction with one arrangement for supplying pulses of current to the cathode, it is obvious that other arrangements utilizing my method may be employed. For example, I have shown the source of the pulses of current supplied to the cathode as being a condenser. Obviously other electrical energy sources may be employed, such as, for example, a high frequency pulsator or oscillator. Likewise various forms of cathode and heating means therefor may be utilized. For example, the cathode may be provided with a separate heater to supply the bias heating power while separate current pulses might be passed to the cathode itself to produce the high temperature peak. Also the cathode might be of the hollow sleeve type heated by high frequency induction currents supplied thereto in pulses. Numerous other modifications will readily suggest themselves from the foregoing description. It is accordingly desired that my invention be given a broad interpretation commensurate with the scope of the appended claims and the status of my invention within the art.

What is claimed is:

1. In a system for producing electrical impulses including an electrical space discharge device having a heated cathode and an anode, means for intermittently applying voltage pulses between the cathode and anode, and means for intermittently supplying pulses of heating current to said cathode to raise said cathode to a temperature of copious thermionic emission substantially in phase with said voltage pulses.
2. In a system for producing electrical impulses including an electrical space discharge device having a heated cathode and an anode, means for intermittently applying voltage pulses between the cathode and anode, means for supplying heating current to the cathode to raise said cathode to a temperature at which the emission of said cathode is insufficient to supply the required peak currents during said voltage pulses, and means for intermittently supplying pulses of heating current to said cathode to raise said cathode to a temperature of copious thermionic emission substantially in phase with said voltage pulses.

LAURENCE K. MARSHALL.
